US00D936663S

(12) **United States Design Patent** (10) **Patent No.:** **US D936,663 S**
Carrigan et al. (45) **Date of Patent:** **** Nov. 23, 2021**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Taylor Gerard Carrigan**, San Francisco, CA (US); **Alan C. Dye**, San Francisco, CA (US); **Christopher P. Foss**, San Francisco, CA (US); **Stephen O. Lemay**, Palo Alto, CA (US); **Marco Triverio**, San Francisco, CA (US); **Christopher Wilson**, San Francisco, CA (US)

(73) Assignee: **Apple Inc.**, Cupertino, CA (US)

(**) Term: **15 Years**

(21) Appl. No.: **29/606,389**

(22) Filed: **Jun. 4, 2017**

(51) **LOC (13) Cl. 14-04**

(52) **U.S. Cl.**

USPC **D14/485**

(58) **Field of Classification Search**

USPC D14/485-495; D5/20, 26, 30, 40, 63-65;

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.

1 Claim, 1 Drawing Sheet
